[57] **CLAIM**

The ornamental design for a stack divider, as shown and described.

DESCRIPTION

FIG. 1 is a top-left perspective view of a stack divider showing our new design folded around a stack which is shown in phantom lines;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a top view thereof in a flat position.

The portions shown in phantom lines including the stack and the embossment are not part of the claimed invention, but are included to show environment.
